UNITED STATES PATENT OFFICE.

EDWARD C. MEIER, OF PHOENIXVILLE, PENNSYLVANIA.

UPRIGHT BOILER.

1,208,812.

Specification of Letters Patent. Patented Dec. 19, 1916.

Application filed August 6, 1915. Serial No. 43,954.

To all whom it may concern:

Be it known that I, EDWARD C. MEIER, a citizen of the United States, residing at Phoenixville, in the county of Chester and State of Pennsylvania, have invented certain new and useful Improvements in Upright Boilers, of which the following is a specification.

My invention relates to improvements in 10 upright boilers, the object of the invention being to provide a boiler of an improved construction embodying a plurality of upright or vertically positioned boiler units all connected to a cross drum at the top of the 15 boiler, and having improved means for regulating the flow of smoke and gases to utilize the full heat units of the fuel.

A further object is to provide an improved construction and arrangement of 20 pre-heater and improved chambers for super-heaters with an improved arrangement of dampers and flues enabling any disposition of the heat units desired.

A further object is to provide a boiler of 25 the character stated which readily lends itself to expansion in the provision of any desired number of boiler units with any number of combustion chambers in accordance with the desire of the trade.

With these and other objects in view, the 30 invention consists in certain novel features of construction and combinations and arrangements of parts as will be more fully hereinafter described and pointed out in 35 the claims.

In the accompanying drawings: Figure 1 is a view in vertical section illustrating my improved boiler. Fig. 2 is a view in vertical section on the line 2—2 of Fig. 1, and Fig. 40 3 is a fragmentary view in vertical section on the line 3—3 of Fig. 2.

In constructing my improved boiler, I provide a cross drum 1 located at the top of the boiler, and connected with any desired 45 number of boiler units 2 located in a vertical or upright position with the boiler units at both sides of the drum, and parallel to each other at both sides of the drum, using as many of such units as desired.

50 In the accompanying drawings, I have shown four boiler units, two being located at each side of the drum, and each boiler unit consists of box headers 3 and 4 connected by water tubes 5, the header 3 connected by telescoping necks 6 with drum 1, and the headers 4 below connected by rela-

tively large strong tubular backbones 7 with the drum 1, said tubes 7 located at an angle to the tubes 2. The boiler units employed in this improved form of boiler are precisely like the boiler unit disclosed in my application executed on even date herewith, except, of course, that I employ but a single drum 1, and connect all of the boiler units thereto.

By reference particularly to Fig. 1, it will be noted that the boiler units at opposite sides of the drum are disposed at an angle to each other, so that a somewhat triangular chamber 8 is formed between the boiler units 2 in which the tubes 9 of a pre-heater 10 are positioned. The headers 11 of the pre-heater 10 are located outside of the walls 12 of the boiler furnace structure or elsewhere as desired, but the water tubes 9 extend 75 through the triangular chamber 8 and receive the direct heat from the products of combustion as will be hereinafter explained. The lower ends of the boiler units are supported on walls 13, and combustion chambers 15 are located at opposite sides of the boiler, and supply the necessary products of combustion. The boiler units 2 are provided with baffles 14 and 16 which compel the smoke and gases from the combustion chambers 15 to circulate through the boiler units as indicated by the arrows. Between the pairs of boiler units at both sides of the drum 1, relatively narrow chambers 17 are formed by tile walls 18 supported between 80 the tubes of the boiler units, and extending to the walls 12 of the furnace structure. In these chambers 17, super-heaters 19 project, said super-heaters being supported at the top of the furnace structure, and projecting 95 into the chamber as shown clearly in Fig. 2. Dampers 20 control inlet openings 21 communicating with the upper portions of the chambers 17 and dampers 22 control outlet openings 23 at the lower portions of said 100 chambers, said openings 23 communicating with the chamber 8. 24 represents smoke outlets in the upper portion of chamber 8 which may communicate with any suitable form of stack (not shown).

In operation, the smoke and gases from the combustion chambers 15 are directed into contact with the water tubes 5 of the several units 2, and the course is controlled by the baffles 14 and 16. After passing through 110 the boiler units, the smoke and gases circulate about the tubes 9 to heat the water in

the pre-heater, and then escapes through the outlets 24. Such proportion of the direct heat as may be desired for super-heating is directed through the chambers 17 by opening dampers 20 and 22 shown clearly in Fig. 1. These chambers therefore become flues through which a direct draft is had, and the smoke and gases at their highest temperature may be directed to the super-heaters as desired. These chambers, of course, receive the same amount of radiated heat in the walls thereof, and any temperature may be had in the chambers in accordance with the super-heated steam desired. It is to be understood, of course, that the several boiler units operate as a single boiler, the water having a free circulation and all of the steam collecting in the drum 1. The tubular backbones 7 operate to strengthen the boiler units and support the drum 1, so that a strong and rigid construction is had.

It will be noted that my improved vertical type of boiler employs my cross drum boiler unit as disclosed in my application for patent executed on even date herewith, and while I have not described any particular manner of supporting the boiler units, it is to be understood that they will be supported in any approved manner, and preferably are hung from overhead supports in the usual accepted manner.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A boiler, comprising a drum, a plurality of pairs of boiler units located at opposite sides of the drum and communicating with the drum, chambers formed between the pairs of boiler units, super-heaters in said chambers, and means for controlling the flow of smoke and gases through said chambers, substantially as described.

2. In a boiler, the combination with a cross drum located at the top of the boiler, of a plurality of pairs of boiler units located at opposite sides of the drum, supported in an upright position and support-

ing the drum between them, said boiler units forming a chamber below the drum and forming other chambers between each pair of boiler units, a pre-heater supported in the first-mentioned chamber, and super-heaters in the last-mentioned chambers, substantially as described.

3. In a boiler, the combination with a cross drum located at the top of the boiler, of a plurality of pairs of boiler units located at opposite sides of the drum, supported in an upright position and supporting the drum between them, said boiler units forming a chamber below the drum and forming other chambers between each pair of boiler units, a pre-heater projecting through the first-mentioned chamber and super-heaters supported on top of the boiler structure and projecting into the last-mentioned chambers, substantially as described.

4. In a boiler, the combination with a cross drum located at the top of the boiler, of a plurality of pairs of boiler units located at opposite sides of the drum, supported in an upright position and supporting the drum between them, said boiler units forming a chamber below the drum and forming other chambers between each pair of boiler units, a pre-heater supported in the first-mentioned chamber, and super-heaters in the last-mentioned chambers, and dampers controlling the flow of smoke and gases through the last-mentioned chambers, substantially as described.

5. In a boiler, the combination with a cross drum located at the top of the boiler, of a plurality of pairs of boiler units located at opposite sides of the drum, supported in an upright position and supporting the drum between them, said boiler units forming a chamber below the drum and forming other chambers between each pair of boiler units, a pre-heater projecting through the first-mentioned chamber, super-heaters on top of the boiler structure and projecting into the last-mentioned chambers, and dampers controlling the flow of smoke and gases through the last-mentioned chambers, substantially as described.

In testimony whereof I have signed my name to this specification in the presence of two subscribing witnesses.

EDWARD C. MEIER.
